UNITED STATES PATENT OFFICE.

MARK A. SMITH, OF EVANSVILLE, INDIANA.

DESIGN FOR A WASH-BOARD.

SPECIFICATION forming part of Design No. 15,809, dated February 10, 1885.

Application filed December 25, 1884. Term of patent 14 years.

To all whom it may concern:

Be it known that I, MARK A. SMITH, a citizen of the United States, residing at Evansville, in the county of Vanderburgh and State of Indiana, have invented a certain new and useful Design for Wash-Boards; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention, and is a front view. Fig. 2 is a vertical section showing the zinc rubbing-plate and a portion of the frame.

This invention has relation to wash-boards, and especially to the rubbing-plates thereof; and it consists in the novel form and configuration of the corrugations, which represent the letters of the alphabet in transverse rows bounded by transverse ridge corrugations, as shown and described.

In the accompanying drawings, the letter A,

designates the wash-board frame, and B the corrugated rubbing-plate, which is the subject of this design. The face is raised in corrugations *c c*, representing the letters of the alphabet in rows, and between these rows in transverse rib corrugations *d*, which are higher than the intermediate letter-form corrugations *c*.

I am aware that it is not new to form raised letters on the rubbing-surface of a wash-board plate, and I do not claim such design, broadly.

What I claim, and desire to secure by Letters Patent, is—

The design for wash-board plates, consisting of the letter-form corrugations *c* in transverse rows, bounded by transverse ridge corrugations *d*, which are higher than the letter-form corrugations, as shown and described.

In testimony whereof I affix my signature in presence of two witnesses.

MARK A. SMITH.
